CLAIM

(58) **Field of Classification Search**

We claim the ornamental design for a display screen or portion thereof with graphical user interface, as shown and described.

USPC ..... D14/485—495

DESCRIPTION

CPC G06F 3/048; G06F 3/0481; G06F 3/04817;

The sole FIGURE is a front view of a display screen or portion thereof with graphical user interface showing our new design.

G06F 3/0482; G06F 3/0483; G06F

The outermost broken lines in the FIGURE show a display screen or portion thereof and form no part of the claimed design. The remainder of the broken lines in the FIGURE depict portions of the graphical user interface and form no part of the claimed design.

3/04842; G06F 3/0485; G06F 3/04855;

G06F 3/0486; G06F 3/0488; G06F

3/04886; G06F 9/4443; G06F 17/211;

G06F 17/212

See application file for complete search history.
